UNITED STATES PATENT OFFICE.

MARTIN F. OEBBECKE, OF PHILADELPHIA, PENNSYLVANIA.

CUFF OR COLLAR BUTTON.

SPECIFICATION forming part of Letters Patent No. 794,636, dated July 11, 1905.

Application filed February 13, 1905. Serial No. 245,449.

To all whom it may concern:

Be it known that I, MARTIN F. OEBBECKE, a citizen of the United States, residing in Philadelphia, Pennsylvania, have invented certain 5 Improvements in Cuff or Collar Buttons, of which the following is a specification.

The object of my invention is to so construct a collar or cuff button that the same can be securely attached to the buttonhole portion of 10 the collar or cuff which has become so worn, frayed, or otherwise enlarged that it will not retain a button inserted in the same in the usual way. This object I attain in the manner hereinafter set forth, reference being had 15 to the accompanying drawings, in which—

Figure 1 a perspective view of a portion of a garment having a buttonhole therein and to which is applied a collar or cuff button constructed in accordance with my invention. 20 Fig. 2 is an enlarged section of said collar or cuff button, showing the manner in which the same is applied to the buttonhole portion of the garment. Fig. 3 is a similar view showing the parts of the button detached from 25 each other, and Figs. 4, 5, and 6 are views illustrating modifications of my invention.

When a buttonhole becomes worn, frayed, torn, or otherwise enlarged to a certain extent, it will not retain a collar or cuff button 30 inserted therein in the ordinary way, since either the head or the back of the button can be pulled through the buttonhole.

My invention comprises a collar or cuff button in which the head and back are separate 35 from each other and are capable of being screwed together, so that a layer or layers of fabric provided with one or more buttonholes can be clamped between the two parts of the button, the latter thereby not only being securely clamped to and held in place upon the 40 fabric, but serving to securely confine together the plurality of layers when it is applied to overlapping portions of a garment and serving also at the same time to attach a 45 collar, cuff, or the like to the garment in the same manner as an ordinary collar-button.

As shown in Figs. 2 and 3, the head 1 of the button has a tubular shank 2, with expanded base 3, and the back of the button consists of 50 a base 4 and a central upwardly-projecting

stem 5, said stem being externally threaded for adaptation to a corresponding internal thread formed in the tubular shank 2 of the head member of the button. As the two parts of the button will usually be formed from gold 55 or other soft metal, it is preferable to provide the hollow shank 2 with an internally-threaded sleeve 6, of iron, steel, or other harder metal, an externally-threaded sleeve 7 being applied to the central stem or shank 5 of the 60 back of the button, so that the threads will resist the wear caused by frequent connection and separation of the two parts of the button. The expanded base 3 of the tubular shank 2 flares outwardly and downwardly, and the 65 back 4 of the button has a central concave recess and upturned edge flange 9, which is preferably milled or roughened on its inner face, as shown at 10. By reason of this construction the back 4 of the button is thin throughout 70 all portions of the same beyond the central stem, and hence is elastic, so that when the pressure of the downwardly and outwardly flaring base 3 of the shank is exerted upon the fabric to press it upon the milled edge of 75 the back the latter can, owing to its resiliency, yield to accommodate inequalities of the fabric. Hence a close grip of the latter between the outer edge of the base 3 and the milled edge of the back 4 is insured, as shown 80 in Fig. 2.

When the improved button is not intended to be used in place of an ordinary collar-button, the shank 2 need not be as long as in an ordinary collar-button, as it will not have to accommodate as many layers or thicknesses of 85 fabric as a collar-button applied in the ordinary way.

Various methods of constructing the two-part collar or cuff button in accordance with 90 my invention will suggest themselves to those skilled in the art, and in Figs. 4, 5, and 6 I have shown several modified constructions. The button shown in Fig. 4 has a thread cut directly upon the central stem or post 5, which 95 projects from the back disk 4 of the button, and the head portion of the button has an internal thread cut directly in the tubular stem or shank 2, while the button shown in Fig. 5 has each of its parts composed of iron, steel, 100

or other relatively hard sheet metal, coated or covered externally with gold or other non-corrosive metal, and in Fig. 6 I have illustrated a construction in which the central 5 threaded stem or post 5^a instead of being integral with the disk 4 of the rear member of the button is secured to said disk by passing the reduced end of the said stem or post through a central opening in the disk and then 10 upsetting or riveting the same on the outer face of the disk.

Having thus described my invention, I claim and desire to secure by Letters Patent—

1. A collar or cuff button comprising a back 15 member with enlarged and elastic base having an upturned peripheral flange, a head member comprising a head, a shank, and a downwardly and outwardly flaring base between whose outer edge and the inner face only of the upturned peripheral flange of the back the fabric is confined, and means for connecting said head member to the back member of the button, substantially as specified.

2. A collar or cuff button comprising a back 25 member with enlarged and elastic base having upturned peripheral flange milled or roughened on its inner face, a head member com-

prising a head, a shank, and a downwardly and outwardly flaring base between whose outer edge and the milled or roughened inner 30 face only of the upturned peripheral flange of the back the fabric is confined, and means for connecting said head member to the back member of the button, substantially as specified.

3. A collar or cuff button comprising a back member with a projecting stem and an expanded base having an upturned peripheral flange, a head member comprising a head, a shank, and a downwardly and outwardly flaring base, and means for connecting said members, the bases of the two members being so disposed that when they are confined together a space will be provided between them, except at the edges, whereby fabric interposed 40 between said heads will be gripped only at said edges, substantially as specified.

In testimony whereof I have signed my name to this specification in the presence of two subscribing witnesses.

MARTIN F. OEBBECKE.
